CURTAIN

Daniel Hughes, Scranton, Pa., assignor to The Scranton Corporation, Scranton, Pa.

Filed Jan. 5, 1972, Ser. No. 215,711

Term of patent 14 years

Int. Cl. D6—10

U.S. Cl. D6—205

The single feature is a face view of a single panel and a portion of an adjoining panel, all other panel sections, including said adjoining portion, being identical to the full panel shown and being arranged in proper relationship, complete the curtain, the partial showing of curtain hooks at the top being for convenience of illustration.

I claim:

The ornamental design for a curtain, as shown and described.
